U.S. Cl. D52—7

FIGURE 1 is a front view of the space condition responsive instrument embodying my new design;

FIGURE 2 is a normal top view of the instrument as shown in FIGURE 1;

FIGURE 3 is a bottom view;

FIGURE 4 is a side view looking from the left at FIGURE 1; and

FIG. 5 is a transverse sectional view taken along line 5—5 of FIG. 1.

The undisclosed side of the space condition responsive instrument is substantially the same in appearance as the side shown in FIGURE 4.

The essential features of my disclosed design reside in the portions shown in full lines in the drawing.

I claim:

The ornamental design for a space condition responsive instrument, substantially as shown and described.
